UNITED STATES PATENT OFFICE.

RALPH C. ENYART, OF CONNERSVILLE, INDIANA, ASSIGNOR TO THE
P. H. & F. M. ROOTS COMPANY, OF SAME PLACE.

DESIGN FOR A ROTARY-PUMP IMPELLER.

SPECIFICATION forming part of Design No. 28,217, dated January 25, 1898.

Application filed January 21, 1897. Serial No. 620,149. Term of patent 14 years.

To all whom it may concern:

Be it known that I, RALPH C. ENYART, a citizen of the United States, residing at Connersville, Fayette county, Indiana, have invented and produced a new and original Design for Rotary-Pump Impellers, of which the following is a specification, reference being had to the accompanying drawings, showing the same.

10 Figure 1 is a perspective view of a rotary-pump impeller, showing my design; and Fig. 2 is an end view of the same on an enlarged scale, these two views being deemed necessary to fully illustrate my design.

15 The leading feature of my design consists in a pair of oppositely disposed lobes whose outer contour curves are true circular arcs, the four extremities of which are equidistant from each other on a circle concentric with 20 the axis of the impeller, the lobe-arcs being joined by the circular waist-arcs of the impeller through small hip-arcs.

25 A indicates the outer contour curves of the lobes, which curves are true circular arcs, the four extremities D of these arcs being equidistant from each other on a circle a, concentric with the center of the impeller.

30 B indicates the circular waist-arcs, and C the hip-arcs joining the extremities of the waist-arcs to the extremities D of the lobe-arcs.

Fig. 2 will serve in more clearly illustrating the leading feature of my design and the manner of describing the essential features of design above mentioned.

35 Describe the established pitch-circle a of the impeller and through its center draw the horizontal b and perpendicular c. On c locate the established lobe extremity d. Bisect f e, getting point D, the four points D being 40 thus equidistant on circle a. With a center i, found on line c, draw lobe-arc A, cutting D D and d. Draw line k, cutting D and i. With l i as a radius and l as a center cut k, getting point m. With m as a center draw 45 hip-arc C, cutting point D. On b locate point j, whose distance from f equals the distance from e to d. With a center found on line b draw arc B, cutting j and meeting hip-arc C. This operation is to be repeated to 50 symmetrically complete the outline of the impeller.

What I claim is—

The design for a rotary-pump impeller as herein set forth.

RALPH C. ENYART.
